ELECTRIC SWITCH

Application filed April 8, 1930. Serial No. 442,532.

In certain electric switches, the switch elements are usually operated by a pull chain, thus turning on or off the light. Such a pull chain is usually made of ball chain which while possessed of many advantages has always been open to the objection that it was liable to catch on switch parts or in the casing opening, rendering a downward pull or any other than a true lineal pull particularly difficult and even impossible at times.

Efforts have been made to overcome these objections, but these efforts have usually consisted of the incorporation of elements which extended through or beyond the casing opening and which were carried by or became an integral part of the switch operating means itself. These devices while more or less satisfactory in result required that special parts be built in the switch, which parts were expensive to manufacture and were impossible of use in the relatively cheap popular switch.

So far as we are aware no one heretofore has conceived of the provision of means separate from the chain itself, but yet adapted to guide the chain while it is moving through the casing opening to operate the switch mechanism. According to the location of the socket, the pull on the chain may be given from any number of different positions and at almost any angle. In order to avoid catching or frictional contact with the casing, it is desirable that the chain be guided outwardly a distance beyond the casing before any angular movement thereof is permitted. By means of our invention we are enabled to secure this result.

In common practice it is customary to attach a string or some other device to the end of the pull chain in order to bring it within reach of the ordinary person. Certain switches such for example as the so-called canopy switch are placed near the ceiling and the string or other means affixed to the end of the chain and by means of which the switch is operated frequently lies over the light globe or shade. The heat of the electric

which extends outwardly a distance from the switch, the cord is made to fall without the circumference of the lamp shade thus overcoming the likelihood of breakage of the cord.

Although we produce our electric switches already equipped with our pull chain guides as disclosed in the drawings, it will be understood that the guide may be sold as an accessory which can easily be applied to the ordinary canopy switch readily obtained on the market.

In the drawings we have illustrated and in the specification described a form of our invention which has proven highly satisfactory and practical in use. Throughout the specification and drawings, like reference numerals are applied to corresponding parts.

In the drawings:

Fig. 1 is a side elevation of a switch equipped with our chain guide in the position it occupies when the chain is in neutral position.

Fig. 2 shows the position assumed by the chain and the guide as the chain is pulled downwardly.

Fig. 3 is a view showing a switch casing equipped to receive our guide, and

Fig. 4 is a view of the guide removed.

We have shown at 1 an ordinary canopy switch of a type readily procured in the market, into which are led through suitable openings (not shown) the usual electrical connections. The casing of the switch illustrated is provided with a threaded member 2 which passes through the usual chain eyelet 3 and extends beyond the casing. Through this member 2 the chain 4 is led, all as shown in Fig. 3.

Our chain guide 5 consists of a tapered spiral spring 5¹ equipped at its inner end with a knurled piece 5² internally threaded as at 5³ to engage the threaded outer surface 2¹ of the member 2.

At its smaller or outer end the chain guide 5 may be provided with a finishing eyelet 5⁴ through which the chain 4 emerges.

The guide 5 normally maintains that por-

it is desired to operate the switch, the chain is pulled from this neutral position and the guide 5 follows the chain. However, because of construction of the guide all sharp angles are avoided, the chain passing freely over the smooth curved surface of the inside of the guide.

The coils of the spring are closely adjacent to each other and an angular pull on the chain 10 causes the larger coils near the casing to separate and spread on the outer side thereof as the guide and chain are pulled at any angle to the normal neutral position of Fig. 1. This very action, however, causes the inner portions 15 of the coils more closely to lie against each other thereby forming a continuously curved path over which the chain must travel as it is drawn from its normal position with relation to the casing. This curved path 20 avoids the friction caused by the chain contacting with or catching on the edges of the eyelet 3 and ensures at all times the free uninterrupted passage of the chain into and out of the casing.

25 The chain is entirely separate from the guide and the guide is neither lengthened nor shortened as the chain is drawn outwardly and sprung back therethrough. However, by reason of its flexible nature the guide adapts 30 itself generally to any angular movement of the chain according to the direction of the pull. This may be understood from Fig. 2 which shows the path followed by the chain and guide in the case of a downward pull.

35 The length of the guide 5 is immaterial provided that its coils are sufficient in number to provide a generally curved surface over which the chain passes in its travel therethrough regardless of the angle of the 40 pull. It is essential that the guide be of sufficiently flexible nature so that it will yield to permit a general angular movement of the chain and yet sufficiently rigid so that the curved surface over which the 45 chain must travel is at all times assured.

Various modifications in our improved switch casing and pull chain guide, the manner of affixing the guide to the casing, and the 50 shape and general construction thereof may obviously be resorted to without departing from the spirit of our invention if within the limits of the appended claims.

What we therefore claim and desire to secure by Letters Patent is:

55 1. In switch mechanism, a casing having a pull chain opening, a chain guide mounted in said opening and a pull chain attached at one end to the switch operating parts and 60 passing through said guide, said guide comprising a tapered coil spring normally extending perpendicular to said casing to hold said chain in alinement with said opening non-extensible as to the lineal movement of said chain, but angularly movable with said chain regardless of the direction of a pull, said coils providing a curved passageway for said chain in its said angular movement whereby interference with the passage of said chain in its lineal movement over said switch and casing parts is avoided.

direction of pull when the chain is pulled to operate the switch.

2. In switch mechanism, a casing having a pull chain opening, a chain guide mounted in said opening and a pull chain attached at one end to the switch operating parts and 70 passing through said guide, said guide comprising a coil spring with said chain regardless of the angular direction of pull when the chain is pulled to operate the switch.

3. In switch mechanism, a casing having a pull chain opening, a chain guide mounted in said opening and a pull chain attached at one end to the switch operating parts, and 80 passing through said guide, said guide movable with said chain regardless of the angular direction of pull when the chain is pulled to operate the switch.

4. In switch mechanism, a casing having a pull chain opening, a chain guide mounted in said opening and a pull chain attached at one end to the switch operating parts and 85 passing through said guide, said guide movable with said chain regardless of the angular direction of pull when the chain is pulled to operate the switch, said guide providing a curved passageway for said chain whereby interference with the passage of said chain in its lineal movement over said switch and casing parts is avoided.

5. In switch mechanism, a casing having a pull chain opening, a chain guide mounted in said opening and a pull chain attached at one end to the switch operating parts and 90 passing through said guide, said guide being non-extensible as to the lineal movements of said chain but angularly movable with said chain regardless of the direction of the pull on the chain, said guide providing a curved 100 passageway for said chain whereby interference with the passage of said chain in its lineal movement over said switch and casing parts is avoided.

6. In switch mechanism, a casing having a pull chain opening, a chain guide mounted in said opening and a pull chain attached at one end to the switch operating parts and 105 passing through said guide, said guide comprising a coil spring normally extending perpendicular to said casing to hold said chain in alinement with said opening non-extensible as to the lineal movement of said chain, but angularly movable with said chain regardless of the direction of a pull, said coils providing a curved passageway for said chain in its said angular movement whereby interference with the passage of said chain in its lineal movement over said switch and casing parts is avoided.

7. In a pull chain switch, a casing having 115 a chain opening, a chain guide disposed in said opening and a chain passing therethrough, said guide adapted to follow the angular movement of the chain regardless 120 of the direction of pull but independent of the 125 chain.

lineal movement of said chain as it is pulled from and returns to neutral position.

8. In a pull chain switch, a casing having a chain opening, a chain guide disposed in said opening and a chain passing therethrough, said guide comprising a tapered coil spring adapted to follow the angular movement of the chain regardless of the direction of pull but independent of the lineal movement of said chain as it is pulled from and returns to neutral position.

9. In a pull chain switch, a casing having a chain opening, a threaded guide member disposed in said opening and extending beyond said casing, a tapered coil spring having a knurled nut on its casing end, said nut being threaded to engage said guide member and a pull chain passing through said guide member and coil spring, whereby said chain is prevented from frictional contact with the casing.

10. In a pull chain switch, a casing having a chain opening, a threaded guide member disposed in said opening and extending beyond said casing, a tapered coil spring having a knurled nut on its casing end, said nut being threaded to engage said guide member and a pull chain passing through said guide member and coil spring, said coil spring being movable angularly but not lineally with said chain as the same is pulled to operate the switch, whereby said chain is prevented from frictionally contacting with the casing.

35 In testimony whereof we affix our signatures.
